[57] CLAIM

The ornamental design for a swimming pool safety ladder, as shown and described.

DESCRIPTION

FIG. 1 is a perspective view of my new novel design of a swimming pool safety ladder;

FIG. 2 is a front elevation view thereof;

FIG. 3 is a side elevation view thereof, the broken line showing of a swimming pool wall being for illustrative purposes only;

FIG. 4 is a rear elevation view thereof; and

FIG. 5 is a top plan view thereof.

FIG. 1

FIG. 5

FIG. 2

FIG. 3

FIG. 4
